UNITED STATES PATENT OFFICE.

JACOB LARSEN, OF CHICAGO, ILLINOIS.

SASH-LOCK.

1,081,538.

Specification of Letters Patent.

Patented Dec. 16, 1913.

Application filed October 2, 1912. Serial No. 723,529.

To all whom it may concern:

Be it known that I, JACOB LARSEN, a citizen of the United States, and a resident of Chicago, in the county of Cook and State 5 of Illinois, have invented certain new and useful Improvements in Sash-Locks; and I do hereby declare that the following is a full, clear, and exact description thereof, reference being had to the accompanying 10 drawings, and to the letters of reference marked thereon, which form a part of this specification.

This invention relates to sash locks adapted to lock the upper and lower sashes of a 15 window in opened or closed position as desired.

It relates particularly to that form of sash locks having a pivoted arm member adapted to be secured to one of the sashes 20 and a catch or lock adapted to be secured to the other sash, and provided with a locking member for engaging the desired pivoted arm and locking the latter and the sash on which it is mounted in any desired one of a 25 plurality of positions with respect to the sash upon which the catch or locking mechanism proper is mounted.

The principal object of the invention is to provide a simple, economical and efficient 30 sash lock.

A further object of the invention is to provide a sash lock comprising a pivoted arm member adapted to be connected with one of the sashes of a window and to swing 35 in a vertical plane to and from upright position, and locking mechanism adapted to be secured to the other sash and having a pivoted catch or locking hook member adapted to swing in a horizontal plane into and out 40 of engagement with said vertically movable, pivoted member of the other sash, and means for securely locking such catch or locking member in locking engagement with the pivoted arm member.

45 Other and further objects of the invention will appear from the following description and claims and from an examination of the accompanying drawings.

The invention consists in the features, 50 combinations and details of construction herein described and claimed.

In the accompanying drawings, Figure 1 is a view in side elevation of a sash lock constructed in accordance with my improvements, showing the same in position to hold 55 the upper and lower sashes locked in closed

position, as it would appear when seen from the outside of the window; Fig. 2, a transverse section taken on line 2 of Fig. 1 looking in the direction of the arrow and showing the parts in the position which they occupy in Fig. 1; Fig. 3, a view in elevation of the parts shown in Figs. 1 and 2 with the relatively long arm of the pivoted arm member in upright position and the locking mechanism on the lower sash in locking engagement with said arm, said parts being positioned to hold the sashes locked in opened position; Fig. 4, a view in vertical section taken on line 4 of Fig. 3 looking in the direction of the arrow; Fig. 5, a plan view of the parts shown in Figs. 1 to 4 inclusive, showing the same in the position illustrated in Fig. 1; Fig. 6, a plan view of the parts shown in Figs. 1 to 5 inclusive, 60 showing the notched pivoted arm members in the position illustrated in Fig. 1, and the locking mechanism of the other sash in releasing position; Fig. 7, a similar plan view showing the horizontally movable pivoted 65 locking hook or locking member in position to be moved longitudinally with respect to the pivot on which it is mounted into engagement with a vertically movable locking arm of the other sash-locking member; Fig. 70 8, an enlarged detail view in vertical section of the locking mechanism of the lower sash, taken on line 8 of Fig. 5 looking in the direction of the arrow; and Fig. 9, an enlarged detail view of the operating lever 75 and the catch or boss for holding the same 80 in operative position.

In constructing a sash lock in accordance with my invention and improvements, I provide a pivoted arm member comprising 95 a relatively long arm *a* and a relatively short arm *b* adapted to extend at an angle with respect to each other. These arms are, by preference, connected in rigid relation to each other or formed in one integral piece 100 and pivotally supported upon one of the sashes, preferably the upper sash *c* of a window, by means of a suitable supporting bracket *d* provided with a horizontally extending pivot pin *e* upon which said 105 arm member is pivotally supported and adapted to swing in a vertical plane so as to enable either the relatively short or the relatively long arm to be swung into upright position, as desired. Each of 110 the arms is provided with one or more notches *f* preferably in the edge adjacent to

or toward the window pane *g*. This pivoted arm member is located on the inside of the window pane and preferably secured to the lower cross piece of the upper sash.

5 In order to provide means for securely locking the pivoted arm member, and thereby the sash upon which it is mounted, in any desired one of a plurality of positions with relation to the other sash of the window, 10 suitable locking mechanism is provided and mounted preferably upon the upper cross piece *h* of the lower sash, and comprises a base plate *i* secured to the sash by means of screws *j* or any desired securing means. The 15 main body portion *k* of the base plate is provided with a suitable top bearing surface *l* having a segmental slot *m* therein, a portion of which slot is in the form of a segment or are of a circle, the center of which coincides 20 with the axial center of the pivoted locking member or hook *n* which is pivotally supported upon the base plate by means of a vertical headed pivot pin or screw *o* mounted in the center of the base plate and projecting upward therefrom and extending through an elongated slot *p* in the hook or locking member *n*. The slot *p* is elongated longitudinally of the locking hook member *n* and the latter is thus adapted to swing in a 25 horizontal plane on the pivot *o* and to slide endwise into and out of locking engagement with whichever one of the arms *a* or *b* is in upright position adjacent thereto. The slot or groove *m* has an inwardly curved end portion *q* which extends nearer the axial center or center of the pin *o* than is the main segmental portion of the groove (see Figs. 5 and 8), and a pin *r* is mounted upon the locking member or hook *n* in position to extend 30 downward into said slot *m* and to be moved into the inwardly extending end portion *q* of the slot by the endwise movement of said locking member (see Figs. 5 and 8). The locking member *n* is provided with a 35 similar segmental slot *s*, shown in Figs. 5 and 8, the main portion of which slot is in the form of an arc of a circle the center of which coincides with the pivot pin *o*, and this slot is provided at one end with an inwardly curved end portion *t* which extends nearer to the axial center of the pivot pin *o* than does the main portion of said slot, and an operating and locking lever *u*, having a 40 suitable perforation therein through which the pivot pin *o* extends, is pivotally mounted on said pivot pin *o* in position to extend over the locking hook or member *n*, and is provided with a depending pin *v* which extends downward into the slot *s* in said locking member *n*, as shown in Figs. 5 and 8. A washer *w* is mounted upon the pivot pin *o* in position to hold the locking lever *u* and thereby the other pivoted locking-member *n* in operative position upon the base plate *i*, so 45 as to permit the operating lever *u* to rotate freely upon its axis formed by said pivot pin, and also permit the rotation of the locking member or hook *n* and its longitudinal movement into and out of locking position. The base plate *i* should be mounted in such position upon the cross piece of the window sash that one edge *y* is flush with the edge of the window sash and in position to be engaged by whichever one of the arms *a* or *b* is raised into position to extend upward adjacent to 50 said base plate. An upwardly projecting boss *z* on the base plate *i* is provided with an inclined shoulder or catch *2*, as indicated in Fig. 9, adapted to engage and securely hold the operating lever *u* in locking position, 55 when said lever is moved to locking position, and into engagement with said boss. 60

The pivoted arm member, comprising the notched or shouldered arms *a* and *b*, is, by preference, so constructed that when the arm *a* is raised to upright position the arm *b* will form a stop and brace adapted to stop the arm *a* when it reaches the proper upright position to enable it to be properly engaged and securely locked in upright position by 65 the locking hook *n*, and the arm *a* is of such construction as to stop the arm *b* in proper upright position to be engaged and securely locked by the hook *n* when the arm *b* is raised. The arm *b* is thus adapted to be engaged by the locking hook *n* when the window sashes are to be locked in closed position, and the arm *a* is adapted to enable the sashes to be locked in any desired one of a 70 plurality of opened positions according to 75 the position of the notch *f* engaged by the hook member *n*. 80

By the above construction and arrangement of elements it will be seen that the swinging of the locking lever *u* upon its pivot in a horizontal plane in the position shown in Fig. 6 will cause the pin *v* on said lever to engage the locking member *n* and swing the latter to releasing position, as shown in Fig. 6, and that the movement of the lever *u* from the position shown in Fig. 6, to the position shown in Fig. 7, will rotate the locking hook member *n* to the position shown in Fig. 7, from which position said locking hook member is adapted to be 85 moved longitudinally and securely locked in locking engagement with the adjacent arm *a* or *b* of the pivoted member on the adjacent sash. In order to enable the locking member or hook *n* to be thus moved longitudinally to its final locking position, in which position the hook portion *3* will extend into the adjacent slot or groove *f*, as shown in Fig. 5, it is only necessary to swing the operating and locking lever *u* from the position shown in Fig. 7 to the position shown in Fig. 5, thus causing the pin *v* on the lever *u* to engage the inwardly curved end portion *t* of the slot *s*, which curved slot portion forms a cam on the locking hook member *n*, 90 95

thus moving the latter endwise from position shown in Fig. 7 to position shown in Fig. 5 and into locking engagement with the adjacent arm *a* or *b*. This endwise movement of the hook or locking member *n* also causes the depending pin *v* on the latter to move into the inwardly curved slot or cam portion *g* of the base plate to the position indicated in Figs. 5 and 8. This movement of the locking lever *u* to the position shown in Fig. 5 causes the lever *u* to be engaged and securely held in position to securely lock the locking member or hook *n* in locking engagement with the adjacent arm *a* or *b* (see Figs. 5 and 9). When the relatively long pivoted arm *a* is in lowered position with the arm *b* in upright position, and the arm *b* is locked in engagement with the base plate *y* by means of the hook or locking member *n*, as shown in Figs. 1 and 5, the window sashes will be locked in closed position and the relatively long arm will be in such position that it will not disfigure the window or detract from the appearance of the sash lock, and the relatively long arm is thus not required to extend upwardly except when the sashes are to be locked in opened position. The longitudinal movement of the locking member or hook *n* enables the adjacent arm *a* or *b* to be firmly drawn into engagement with the adjacent edge *y* of the base plate *i* and securely held in such position in such a manner as to prevent all rattling of the sashes with respect to each other, and securely lock the sashes in any position in which they are adjusted.

I claim:

1. In a sash lock, the combination of two rigidly joined arm members arranged at right angles to each other, and one of which is longer than the other, said arm members being provided with a plurality of notches, means for pivotally connecting said arm members to a sash at their joined ends,

adapted to permit either arm member to be placed in upright position, a base plate adapted to be secured to an adjacent sash, and a locking member pivotally mounted on the base plate, said locking member having a lateral projection at its free end and adapted to have swinging and endwise movement to bring said projection in locking engagement with a notch of the arm member which is placed in an upright position, and to draw the arm member against the adjacent margin of the base plate.

2. In a sash lock, the combination of two rigidly joined arm members arranged at right angles to each other, and one of which is longer than the other, said arm members being provided along their rear margins with a plurality of notches, means for pivotally connecting said arm members to a sash at their joined ends, adapted to permit either arm member to be placed in upright position, a base plate adapted to be secured to an adjacent sash, a locking member pivotally mounted on the base plate, said locking member having a lateral projection at its free end and adapted to have swinging movement to bring said projection into position for locking engagement with a notch of the arm member which is placed in an upright position, and means acting on said pivoted locking member to give endwise movement to the same to engage the said lateral projection of said locking member and to draw the forward margin of the arm member against the rear margin of the base plate.

In testimony, that I, claim the foregoing as my invention I affix my signature in the presence of two witnesses, this 28th day of September A. D. 1912.

JACOB LARSEN.
